UNITED STATES PATENT OFFICE.

HANS M. BOE, OF MINNEAPOLIS, MINNESOTA.

PUMP CONSTRUCTION.

Application filed August 23, 1926. Serial No. 130,989.

This invention relates generally to improvements in pumps, having an overhanging discharge nozzle, a drip-pipe engageable with the discharge nozzle, and rotatably stepped within the base of the pump, and in 5 communication with a return passage, for delivering the drippings to the reservoir. The drip pipes of these pumps may be swung outwardly or away from the delivery end or 10 nozzle of the pump to permit introduction of a receptacle beneath the delivery nozzle. These tubular members, as drip pipes, are generally arranged to yieldably engage the discharge end of the pump, as a stop, and a 15 spring is provided to normally hold the same in drip-catch position. An objection to the spring operated devices as now made, is that drilling is necessary either in the base of the pump or in the drip pipe or both, in 20 order to attach the springs. Moreover there is considerable time wasted in assembling the springs, because they are usually placed, either upon the pump, or mounted upon and attached to the drip-pipe.

25 An object of this invention is to provide a tension element torsionally active for yieldably holding the drip-pipe in catch position, which has no positive connection either with the drain pipe or with any part 30 of the pump, and which can be assembled, by simple insertion, in an axial direction.

Another object is to provide a device located within the tubular or passage portion 35 of the pump, and drip pipe, and adapted for assembly by first inserting one end into a passage in the base of the pump, and by engaging the lower end of the drain pipe over the upper end of the spring element, in 40 a direction axially of the drain passage and of the drain pipe, and then securing the pipe for oscillation.

Features of the invention include the construction of the element per se; its mode of placement within the drain pipe; and the 45 means for securing the device in rotative position and against axial translation.

Figure 1 is a vertical sectional view showing my invention applied to the drain pipe of a pump.

50 Figure 2 is a plan view showing the positional relation of my spring to certain parts of the pump.

Figure 3 is a detail showing how the drain tube is connected with the pump for rota-

tion, but against withdrawal in an axial direction.

Figures 4 and 5 are detail views of the spring element taken in planes at right angles to one another.

Figure 6 is a detail plan view of the 60 spring element.

In applying my invention to a liquid dispensing apparatus, I arrange the device in tensioned relation within the drain tube, as 65 a base, shown in Figures 1 and 2.

The numeral 1 designates a base as a coupling member adapted for threaded connection with the top of a reservoir or with a tube supported by a reservoir. This base has a bore or return passage 3, leading upwardly and communicating with an extension 4, which in this instance forms a socket to receive the lower end of the drain pipe. In the type of pump to which the invention is applied, a horizontal delivery arm 6 is 75 provided at the top through which the oil flows to be dispensed through a nozzle 7, in this instance vertically disposed.

The drain pipe or tube has an intermediate angularly related portion 10, and mutually parallel terminal portions 12 and 13. The lower portion is situated within the extension 4, is rotatable therein, and communicates with the passage 3 of the base. The upper portion 12 of the drain pipe is notched as at 15 on one side, the opposite side being adapted to engage the nipple or nozzle as a stop. The arrangement is such, however, that the drain tube can be drawn laterally into non-interfering position. I provide a 80 means, a feature of this invention, for mounting the drain tube, to permit rotation, and to prevent accidental withdrawal of the tube from its socket in a direction axially thereof. For this purpose, I provide a collar or sleeve 20 having an arcuate slot 21 therein, through which a screw 22 loosely projects and has threaded engagement with the extension 4. The upper part of the element 20 has a reduced tubular extension 25 85 brazed or otherwise attached to the tube, to make a leak-proof joint. After the tube has been placed in its socket and the screw 22 engaging with the extension 4 and through the slot 21, the tube is rotatably held, against 90 translation, axially.

My improved spring element has a main portion 30, and terminally, angularly re-

lated portions respectively 31—32. Each of these terminal portions is bent, respectively at 33—34 to facilitate insertion, and it will be noted that these bent portions, as loops, lie in planes substantially perpendicular to one another. (See Figures 2 and 6.) The angled portions 31 and 32, each form an obtuse angle with the intermediate portion 30. The portion 32 is adapted to lie within the passage 3 at an angle to the axis of rotation of the tube. The upper portion 31 of the spring element lies within the angled portion 10 of the tube. (See Figure 1.) The result is that the portions 31—32, as radial arms, engage the tube and passage 3 respectively to prevent complete rotation of the tube, but subjecting the element to greater torsion when the tube is turned in a direction away from its stop engagement with the nozzle. The wire is bent so that the arms 31 and 32 are radially related substantially as shown in Figure 6. After assembly, the spring element is maintained under tension, as shown in Figure 2. The difference in this angular relation can be seen by comparing Figures 2 and 6.

In assembling the device, the spring element is first engaged within the socket, as shown in Figure 1 with its lower portion disposed radially with respect to the axis of rotation of the tube. The tube is then engaged over the upwardly extending end of the spring element and forced downwardly, during which operation the intermediate and upper terminal portions are slightly straightened in respect to one another, but subsequently assume the normal angular relation, to lie substantially as shown in Figure 1. The screw 22 is then properly introduced to secure the tube against axial displacement.

The assembly is very simple and is made in a direction axially of the drain tube. This type of spring and assembly can be used in other environments, without departing from the spirit of the invention, and such other uses are contemplated.

The loop 23 is formed to cause the bent portion 31 to lie adjacent the lower side of the angular portion 10 of the tubular member, to prevent such straightening of the wire, as would annul its torsional action. Instead of bending the wire upon itself as shown to form the loop, any formation may be used which will tend to hold the portion of the wire mentioned, toward the lower side of the bent portion 10 of the tubular member. The position of the loop 33 should be substantially as shown in Figure 2, that is, it should have substantially a diametric relation to the tube.

It will be seen that the angle α (see Figure 1) should not too nearly approach a straight angle.

I claim as my invention—

1. In combination, a base member having

an angled passage, an angled tubular member, having one portion rotatably engaging within one portion of said passage, a stop engageable by said tubular member, and a torsion element wholly within the passage and tubular member having angled portions respectively engaged within said passage and tubular member and under tension to force the tube against the stop. 70

2. In combination with a barrel-pump including an angled return passage and a delivery spout, an angled drip-pipe rotatably mounted and leading into the return passage, and adapted to engage the spout as a stop in position to catch the drippings, 80 and a torsion spring element, as a wire, having an angled portion respectively in said angled passage and drip tube, and under tension to yieldably hold the drip tube against the spout in receiving position, and 85 freely releasable by withdrawing the drip pipe in an axial direction.

3. In combination a base member, having an angular passage, an angled tubular member having one portion telescopically engaging within one portion of said passage for rotation, a stop for said tubular member, and a torsion element having an angled portion respectively in said angled passage and tubular member, arranged to force the tube against the stop, said torsion element having terminal portions, each at an angle obtuse to the central portion, said portions being only frictionally engaged against the 100 walls of the passage and tubular member.

4. In combination a base member, having an angular passage, an angled tubular member, having one portion engaging with one portion of said passage for rotation, a stop for said tubular member, and a torsion element having angled portions respectively in said passage and tubular member, arranged to force the tube against the stop, said torsion element having terminally angled and terminally looped portions, said 105 loops being in planes substantially perpendicular to one another.

5. A support having a bore, a bent tube rotatable in said bore, and a wire having angularly related portions arranged to be non-rotatably held respectively in said pipes and bore said angularly related portions being radial in respect to the axis of rotation of the tube. 115

6. In combination a support having a bore, a tubular member rotatable in the bore, and having intermediate portion angularly related to the axis of rotation, and a wire element having a terminal portion within said angularly related portion and having an intermediate portion in the axially disposed portion of the tube, said wire having its opposite terminal portion lying within said bore at an angle to the axis of 125 rotation of this tubular member. 130

7. In combination a base member, having an angular passage, an angled tubular member, having one portion engaging with one portion of said passage, for rotation, a stop for said tubular member, a torsion element having angled portions respectively wholly within said angled passage and tubular member arranged to force the tube against

the stop, and a sleeve sealingly attached to said, tubular member, and rotatably engaged over said base, and rotatably, but non-translatably secured thereto. 40

In witness whereof, I have hereunto set my hand this 18th day of August, 1926.

HANS M. BOE.
